UNITED STATES PATENT OFFICE.

LEO DAFT, OF GREENVILLE, NEW JERSEY.

ELECTRIC MOTOR.

SPECIFICATION forming part of Letters Patent No. 336,629, dated February 23, 1886.

Application filed May 26, 1885. Serial No. 166,718. (No model.)

To all whom it may concern:

Be it known that I, LEO DAFT, a citizen of the United States, residing at Greenville, in the county of Hudson and State of New Jersey, have invented certain new and useful 5 Improvements in Electric Motors, of which the following is a specification.

My invention relates to electric motors, and more particularly to the means for reversing 10 the same; and it has for its object to improve the construction of the reversing mechanism or brush-carriers, so that they may be readily and easily operated, and so that the brushes shall bear upon the commutator when in use 15 in such a manner as to secure the highest efficiency and the least wear at the points of contact, and so that they may be readily thrown out of contact with the commutator when desired.

20 To these ends my invention consists in a mechanism constructed substantially as hereinafter pointed out.

In the accompanying drawing is shown a side view of one well-known type of motor 25 with my improvements attached.

It is well known that in the use of electric motors—such, for instance, as are employed on electric locomotives—it is necessary to frequently change or reverse the direction of rotation of 30 the armature, and one convenient way of so doing is to change the relative positions of the brushes on the commutator, so as to cause the current to pass through the coils of the armatures in different directions. It often happens, also, that it is desired to withdraw the 35 current entirely from the commutator, as when the locomotive is running by its momentum alone.

It is well recognized that the most efficient 40 way of placing the brushes is to have them inclined to the face of the commutator in the direction of its rotation, and not only does the current pass with less resistance, but the wear upon the brushes is much less than when they 45 are placed in a radial line to the axis of the commutator or at an inclination opposed to the direction of rotation of the armature.

In carrying out these improvements I construct the brushes and make the circuit-connections as follows: In the drawing, the field-magnets are represented by F, the armature 50 by M, with the commutator O fixed upon the

armature-shaft P, supported in the frame Q. Also loosely supported upon the armature-shaft is the rocking lever B. Secured to the ends 55 of this lever, by pins or bolts passing through insulating-bearings b, are the guide-levers A, the outer ends of which are provided with guides a, running in slots c in the extension of the frame Q. The brush-carriers D are rigidly secured to the inner ends of the guide-levers A, and properly insulated therefrom, and each brush-carrier is provided with a pair of brushes, as 1 3 and 2 4, placed at an angle to each other, as shown. Some suitable operating 60 means is connected to the rocking lever, as the rod E, and attached handle, E', moving over the sector E². The circuit-connections are made so that one brush on each side of the commutator, as 1 and 2, have a common 65 terminal, which, for example, in the drawing is shown to be connected to the inner end of the field-magnet coil, and similarly the brushes 3 and 4 are connected to the line-circuit.

From this construction it will be seen that 70 when the reversing-lever is thrown over, as shown in the drawing, the brushes 1 and 4 only will bear upon the commutator at diametrically-opposite points, and the direction 75 of rotation of the armature will be that indicated by the arrow, and it will be evident when the rocking lever is thrown over to the other extreme of the sector that the brushes 2 and 3 will engage with the commutator at diametrically-opposite points, and the direction 80 of rotation of the armature will be reversed by the evident reversal of the relations between the currents passing through the armature and the field-magnets.

It will be observed that whatever the direction 85 of the armature the brushes will bear upon the commutator in such a position as to produce the best results electrically and 90 produce the least wear. When it is desired to allow the motor to run by its momentum or otherwise, independent of the current, the reversing-lever will occupy an intermediate position on the sector, and all the brushes will be free from the commutator.

It is evident that the construction and arrangement of the mechanical devices may be varied from that shown to meet the exigencies of the particular construction of the various motors without departing from the spirit 105

of my invention, and that parts of the mechanism described may be used alone or with other equivalent devices.

What I claim is—

5. 1. In an electric motor, a rocking lever having a pair of brushes at each end arranged with their inner ends projecting from each other, one of the brushes of each pair having a common terminal, and mechanism, substantially as described, whereby each diametrically-opposite pair may be brought into contact with the commutator at an angle to the direction of rotation of the commutator, as set forth.
15. 2. The combination, in an electric motor, of a rocking lever, guide levers secured to the ends of the lever and working in guide-slots, a pair of brushes secured to the rods, and operating devices, substantially as described, whereby either pair of the diametrically-opposite brushes may be brought into contact with the commutator, as set forth.

3. The combination, in an electric motor, of an armature-shaft and commutator secured thereto, a rocking lever on said shaft, guide-levers secured to the ends of said lever and working in slots in the frame of the machine, a pair of brushes secured to the guide-levers, having outwardly-projecting rods, and one brush of each pair having a common terminal, and a hand-lever for changing the position of the brushes, so that they will bear upon the commutator at an angle to the direction of rotation of the same, or so that none of the brushes will touch it, substantially as described. 35

In testimony whereof I have signed my name to this specification in the presence of two subscribing witnesses.

LEO DAFT.
